Patented May 18, 1915.

UNITED STATES PATENT OFFICE.

JOSEPH E. MILCOFF, OF LEETSDALE, PENNSYLVANIA.

WRENCH.

1,140,276.

Specification of Letters Patent.

Patented May 18, 1915.

Application filed December 1, 1913. Serial No. 803,949.

To all whom it may concern:

Be it known that I, JOSEPH E. MILCOFF, a citizen of the United States, residing at Leetsdale, in the county of Allegheny and State of Pennsylvania, have invented new and useful Improvements in Wrenches, of which the following is a specification.

The present invention relates to improvements in wrenches, the object of the invention being to provide means associated with a jaw which is mounted for slidable movement upon the toothed shank of a stationary jaw, whereby the said movable jaw may be easily and quickly locked upon the shank to properly space the heads of the wrench to engage with nuts or other objects of varying diameters, and the improvement resides in the construction, combination and arrangement of parts set forth in the following specification and falling within the scope of the appended claims.

In the drawings: Figure 1 is a side elevation of a wrench constructed in accordance with the present invention, the movable jaw being shown in section and its pawl being brought into engagement with one of the teeth of the shank of the stationary jaw, Fig. 2 is a similar sectional view showing the tooth of the pawl out of engagement with the teeth of the shank to permit of the adjustment of the movable jaw upon the shank, Fig. 3 is a longitudinal sectional view on the line 3—3 of Fig. 1, and looking toward the arrows, Fig. 4 is a detailed sectional view, illustrating the means for locking the handle of the cam roller to hold the pawl either in locking or unlocking position with relation to the teeth of the stationary jaw. Fig. 5 is a sectional view, similar to Figs. 1 and 2, but illustrating a modified form of pawl. Fig. 6 is a perspective view of the pawl shown in Fig. 5. Fig. 7 is a perspective view of the cam roller.

Referring now to the drawings in detail, 45 1 designates the head of the stationary jaw and 2 the shank for the jaw 1. The shank is provided upon what may be termed its front face with transversely arranged teeth 3.

The numeral 4 indicates the slidable jaw. 50 This jaw is provided with a bore or passage 5 for the reception of the shank 2, the said passage conforming in shape to the cross sectional contour of the shank 2. The jaw proper is formed with a chamber 6 which 55 opens into the passage 5 at the rear portion of the jaw 4, as is indicated by the numeral

7. The passage has one of its sides formed with an opening which is preferably threaded and which is adapted to receive a threaded closure 8. The closure 8, as well as the 60 opposite side of the chamber 6 has registering rounded openings 9, the same being adapted to provide bearings for a laterally extending shaft 10 provided upon a roller 11.

The numeral 12 indicates one form of the 65 pawl. This pawl has its enlarged end or its end opposite its engaging tooth 13, formed with a round opening 14 for the reception of the cam roller 11. It should be here stated that the front wall 14' of the chamber 6 is 70 round, while the back wall 15 is inclined or beveled to the opening 7, and the pawl 13 has its opposite edges curved to its engaging tooth 13. The pawl is provided with a rounded knob or enlargement 14'' which 75 normally contacts with the inclined wall 15, a spring 17 being arranged within the casing and exerting a tension upon the pawl below its tooth 13 to swing the pawl and retain its enlargement 14'' in such engagement. The 80 shaft 10 which projects through the closure 8 is provided with an angular handle 18 whereby the cam roller 11 is operated, and it will be noted that by actuating the handle to revolve the cam roller 11, the pawl 85 will be forced either toward or away from the teeth 3 of the shank 2 to lock or unlock the slidable jaw from the shank of the stationary jaw. The arm of the crank handle is arranged a suitable distance away from 90 the side of the movable jaw, and the said arm opposite its juncture with the handle proper is recessed for the reception of a spring pressed pin 19, while one of the sides of the jaw is formed with spaced depressions 20 which are arranged concentrically 95 thereon with relation to the shaft 10, and are thus rotated to receive the pin, when the handle is swung so that the pawl may be sustained in a locked or unlocked position 100 with relation to the shank 2 of the jaw 1.

In Fig. 5 I have shown a slightly modified form of the pawl 12'. In this figure the pawl is substantially similar in construction to that previously described, except that 105 both of the opposite edges of the said pawl are provided with rounded lugs A and B. The lug B bears against the rounded front wall of the chamber while the opposite lug A engages with the angular back wall of 110 said chamber, the lugs A and B resting upon the opposite converging walls of the cham-

ber to guide the dog 1 when the same is moved by the operation of the cam, to direct its tooth C into engagement between the teeth 9 of the shank of the wrench, or to bring the said tooth C out of such engagement.

From the above description taken in connection with the accompanying drawings, the simplicity of the device as well as the advantages thereof will, it is thought, be perfectly apparent to those skilled in the art to which such inventions appertain without further detailed description.

The jaw 14 is provided with an opening 15 which communicates with the chamber 6. The opposite ends provided by the opening are preferably inclined toward each other, as indicated by the characters *a*, and the said opening is of sufficient a size to permit 20 of the insertion of the pawl within the chamber 6. The opening is normally closed by a cap *b* and which has its opposite transverse edges inclined, as at *c*, to fit snugly over the inclined transverse edges *a*, while 25 suitable headed securing elements *d* pass through suitable openings in the jaw adjacent the pivoted or inclined edges of the opening thereof, the heads of the said elements engaging with the opposite trans- 30 verse edges of the cap *b*.

Having thus described the invention, what I claim is:

1. A wrench including a stationary jaw having a toothed shank, a movable jaw upon 35 the shank, a cam roller arranged in an opening in the movable jaw, a shaft for the cam journaled in bearings in the jaw, a handle for the shaft, the opposite walls formed by the opening being flared toward the outer 40 end of the opening and the said outer end communicating with the teeth of the shank, a pawl journaled upon the cam roller, said pawl being formed with a knob which normally contacts with one of the walls pro- 45 vided by the opening and whereby the toothed or engaging end of the pawl is guided into or out of engagement between

the teeth of the shank when the shaft is rotated to actuate the cam roller and pawl.

2. A wrench including a stationary jaw 50 having a toothed shank, a movable jaw upon the shank, a pawl carried by the movable jaw for co-acting with the teeth of the shank, a cam roller journaled in bearings upon the movable jaw and passing through a round opening in the pawl, said movable jaw having inclined guide walls, a knob upon one of the edges of the pawl, and a spring contacting with the opposite edge of the pawl to space the pawl proper from 55 the guide walls and permit of the pawl being brought into or out of engagement with the teeth of the shank when the cam roller is rotated.

3. In a wrench, the combination with a 60 toothed shank of a jaw slidably mounted upon the shank, said jaw having a chamber which communicates with the teeth of the shank, the opposite walls of said chamber being inclined, a cam roller within the chamber, said roller being provided with laterally extending shafts which are arranged in bearings in the said walls of the chamber, a pawl mounted upon the cam roller, said pawl having a knob adjacent its engaging 65 face which contacts with one of the walls of the chamber, a spring upon the second wall contacting with the pawl to force its knob into engagement with the first mentioned wall of the chamber, a cam handle 70 for one of the lateral shafts of the cam roller, a spring pressed pin within the handle, and spaced openings upon the side of the movable jaw to receive the spring pressed pin to hold the crank handle after 75 the same has been rotated to bring the pawl into or out of tooth engaging position.

In testimony whereof I affix my signature in presence of two witnesses.

JOSEPH E. MILCOFF.

Witnesses:

T. HENLE,
RUDOLF CRULAK.
